UNITED STATES PATENT OFFICE.

MILTON B. KIRKER, OF PITTSBURG, PENNSYLVANIA, ASSIGNOR, BY MESNE ASSIGNMENTS, TO THE PITTSBURG TUBULAR STEEL WHIFFLETREE COMPANY, OF SAME PLACE.

WHIFFLETREE.

SPECIFICATION forming part of Letters Patent No. 392,273, dated November 6, 1888.

Application filed February 24, 1887. Renewed October 10, 1888. Serial No. 287,784. (No model.)

To all whom it may concern:

Be it known that I, MILTON B. KIRKER, residing at Pittsburg, in the county of Allegheny and State of Pennsylvania, a citizen of the United States, have invented or discovered certain new and useful Improvements in Singletrees and Doubletrees, of which improvement the following is a specification.

In the accompanying drawings, which make part of this specification, Figure 1 is a view in side elevation of a singletree embodying my invention. Fig. 2 is a similar view of a doubletree. Fig. 3 is a longitudinal section through the doubletree. Fig. 4 is a transverse section on the line *x x*, Fig. 2.

The invention herein relates to certain improvements in the manufacture of singletrees, doubletrees, and other like articles; and it consists, generally stated, of a tube tapering from its middle portion toward each end, and having suitable fittings secured therein in such a manner as to avoid all liability of their becoming loosened under ordinary conditions of wear or use or by reason of exposure to atmospheric influences.

Singletrees and doubletrees are ordinarily formed of some tough wood, and the fittings therefor are usually secured by shrinking them upon the wood or by means of bolts or rivets. The latter method of securing the fittings—*i. e.*, by bolts or rivets—is objectionable, not only on account of the weakening of the wood by the holes formed by the rivets, but also on account of the bolts or rivets becoming loose.

In shrinking the fittings on they are heated to approximately a dark cherry-red, then slipped onto the wood, and rapidly cooled by the application of water. This manner of securing the clips is temporarily unobjectionable; but as the hot metal chars the surface of the wood in contact therewith the blows and other rough usage to which these articles are subjected cause a comminution or pulverization of the charred surfaces and a consequent loosening and dropping off of the fittings. Singletrees and doubletrees have also been made of metal tubes, the fittings therefor being either secured to the tubes by bolts or rivets or else forged thereon, both methods being objection-

able on account of the time and labor required therefor.

In the practice of my invention I take a wrought-metal tube or pipe of suitable length and diameter, and by means of suitable tools gradually taper it from its middle portion toward its ends, thus forming the bar 1. The central fitting, 2, formed of cast-iron and malleableized, the internal diameter of the part thereof designed to encircle the bar being a little less than the external diameter at its middle portion, is heated to a cherry-red, thereby expanding it, and is slipped over one end of the bar, and, being adjusted accurately in place on the middle portion of the bar, is cooled. The contraction of the fitting will cause it to adhere so firmly to the bar that nothing short of its destruction or a reheating can move it from place. The tapering of the bar from its center to the ends is expedient for facilitating the slipping on of the middle fitting, for the reason that as the fitting is only a small fraction of an inch larger than the bar, even when expanded, it would be liable to catch on the bar at some point other than that desired were the bar of uniform diameter throughout its entire length. I prefer to leave a portion, 3, at the middle, equal in length to the width of the fitting, flat, and thereby avoid the necessity of giving a double taper to the inner surface of the fitting, in order to get a uniform bearing on the bar, as would be necessary if the tapering surfaces met and formed an angle at the middle of the bar. The end fittings, 4, having their sockets tapering to correspond to the taper of the bar, are secured in place in a similar manner.

As I do not wish to limit myself to any particular shape or construction of fitting, a further description of the fitting seems unnecessary. By the term "fitting," as hereinbefore used, I mean those devices which are placed on the middle and ends of singletrees and the draft-bars of doubletrees for the purpose of connecting the singletrees to the draft-bars or of connecting the tugs or chains of a harness to the singletrees.

Neck-yokes for wagons which are very similar to singletrees can readily be made in the

manner above described, and are therefore considered as within the scope of the invention herein.

I claim herein as my invention—

- 5 1. A singletree or draft-bar having, in combination, a metal tube tapering from its middle toward the ends and malleable cast-iron fittings shrunk upon the metal tubes, substantially as set forth.
- 10 2. A singletree or draft-bar having, in com-

bination, a metal tube having a straight middle portion, and tapering thence each way to its ends, and malleable cast-iron fittings shrunk upon the metal tubes, substantially as set forth.

In testimony whereof I have hereunto set 15 my hand.

MILTON B. KIRKER.
